(57) **CLAIM**

We claim the ornamental design for an off-road vehicle, as shown and described.

DESCRIPTION

FIG. 1 is a top, front, and left side perspective view of an off-road vehicle as shown and described;

FIG. 2 is a top, rear, and right side perspective view thereof;

FIG. 3 is a left side elevational view thereof;

FIG. 4 is a right side elevational view thereof;

FIG. 5 is a top plan view thereof;

FIG. 6 is a front elevational view thereof; and,

FIG. 7 is a rear elevational view thereof.

The portions of the off-road vehicle shown in broken lines form no part of the claimed design.
